UNITED STATES PATENT OFFICE

105,780

DESIGN FOR A COAT

Isadore Savodnik, New York, N. Y.

Application July 10, 1937, Serial No. 70,353

Term of patent 3½ years

To all whom it may concern:

Be it known that I, Isadore Savodnik, a citizen of the United States of America, residing in Manhattan, county and State of New York, have invented a new, original, and ornamental Design for a Coat, of which the following is a specification, reference being had to the accompanying drawing, forming part thereof, wherein,

The characteristic feature of my design resides in the contrastingly bound triple revers on the coat, as shown.

I claim:

The ornamental design for a coat, substantially as shown and described.

ISADORE SAVODNIK.
